UNITED STATES PATENT OFFICE.

EDWARD W. CARNES, OF CHICAGO, ILLINOIS, ASSIGNOR TO AMERICAN CAN COMPANY, OF NEW YORK, N. Y., A CORPORATION OF NEW JERSEY.

SHEET-METAL DISINFECTANT CABINET OR HOLDER.

No. 910,270.

Specification of Letters Patent.

Patented Jan. 19, 1909.

Application filed September 24, 1908. Serial No. 454,642.

To all whom it may concern:

Be it known that I, EDWARD W. CARNES, a citizen of the United States, residing in Chicago, in the county of Cook and State of Illinois, have invented a new and useful Improvement in Sheet-Metal Disinfectant Cabinets or Holders, of which the following is a specification.

My invention relates to cabinets or holders for disinfectants or other like materials.

The object of my invention is to provide a sheet metal disinfectant cabinet or holder of a simple, efficient and durable construction, which may be readily and conveniently attached to the wall or other support, and in which the hanger or attaching means will prevent the cabinet being opened or the contents tampered with.

My invention consists in the means I employ to practically accomplish this object or result, as herein shown and described, and more particularly specified in the claims.

In the accompanying drawing forming a part of this specification, Figure 1 is a vertical sectional view of a sheet metal disinfectant cabinet or holder embodying my invention. Fig. 2 is a vertical section on line 2—2 of Fig. 1. Fig. 3 is a cross section on line 3—3 of Fig. 2 and Fig. 4 is a cross sectional view similar to Fig. 3, illustrating a modification.

In the drawing, 1 represents the back plate of my germicide or disinfectant holder or cabinet, the same having projecting wings 2 at its upper and lower ends, and projecting wings 3, 3 at its sides, said wings being provided with holes 4 for the hangers or supporting devices 5, preferably screws, to project through.

6 is the body of the sheet metal cabinet or holder, the same comprising an upright front 7, upright sides 8 and end members 9 and 11, the front and side edges of which are interfolded or seamed to the side and front members of the body at the ends thereof, by interengaging folded flanges 10, on the end members 9, and 11, on the front members 7 and side members 8, so as to securely unite the upper and lower end members to the upright front and side members or walls 7 and 8, 8. The side members or walls 8, 8 are each provided with laterally projecting wings 12 and each furnished with a guide flange or fold 13 at its outer longi-

tudinal edge to engage the outer longitudinal edges of the back plate, or of the wings 12 thereof. The end plates or members 9 and 11 of the cabinet body are provided with longitudinally projecting wings 14, the lower one of which is furnished with a guide flange or fold 15 to engage the lower edge of the lower wing on the back plate 1. The laterally projecting wings 12 and end wings 14 on the body member of the cabinet are provided with holes 16 registering with the holes 4 in the corresponding wings of the back plate to receive the hangers or screws 5 by which the cabinet is attached to the wall or other upright support 17 to which it is secured. The body member of the cabinet is furnished with a series of perforations 18, the same being preferably located at the upper end of the side walls 8. The disinfectant or germicide 19 in the cabinet is preferably of a conical shape, as indicated in the drawing.

In the modification illustrated in Fig. 4, the guide flanges or folds, through which the body member of the cabinet is slidably and detachably connected with its back plate, are illustrated as being formed on the back plate instead of upon the wings of the body member, this being an equivalent construction. When the body member is applied to the back member of the cabinet and secured to the wall or other support 17 by the screws or other hanger devices 5 which extend through the registering openings in the wings of the body and back members, the two members are permanently fixed together so that the one cannot be removed from the other without removing the hangers by which the cabinet is connected to its support. This prevents the cabinet being opened or its contents being tampered with.

I claim:

1. A sheet metal cabinet or holder for germicides or disinfectants, consisting in a body member furnished with perforations and provided with laterally projecting wings at its sides and longitudinally projecting wings at its ends, and a back member furnished with corresponding wings, the wings of the body and back members having registering openings and hanger devices extending through the openings of both members, the wings of one of said members having

guide flanges engaging the other to slidably connect the two together, substantially as specified.

2. A sheet metal cabinet or holder for germicides or disinfectants, comprising a body member, furnished with laterally projecting wings, and a back member, said wings and back member having registering openings through the same, and a hanger device extending through said openings to lock the members together, substantially as specified.

3. A sheet metal cabinet or holder for germicides or disinfectants, comprising a body member furnished with laterally projecting wings and a back member, said wings and back member having registering openings through the same, and a hanger device extending through said openings to lock the members together, one of said members having guide flanges engaging the other to slidably connect the members, substantially as specified.

4. A sheet metal cabinet comprising a body member furnished with a projecting wing provided with a hanger opening, a back having an opening registering with the opening in the wing of the body member, and a hanger extending through said openings in the wing and body members, substantially as specified.

5. A sheet metal cabinet comprising a body member furnished with a projecting wing provided with a hanger opening, a back having an opening registering with the opening in the wing of the body member, and a hanger extending through said openings in the wing and body members, one of said members having guide flanges engaging the other member to slidably connect the same, substantially as specified.

EDWARD W. CARNES.
